UNITED STATES PATENT OFFICE.

ANTOINE LAVOCAT, OF LYONS, FRANCE.

COMPOSITION FOR CLOSING PUNCTURES IN PNEUMATIC TIRES.

SPECIFICATION forming part of Letters Patent No. 618,694, dated January 31, 1899.

Application filed September 28, 1898. Serial No. 692,115. (No specimens.)

To all whom it may concern:

Be it known that I, ANTOINE LAVOCAT, chemist, a citizen of the Republic of France, residing in Lyons, (Rhône,) France, have invented a new and Improved Puncture-Closing Composition for Use in Connection with Pneumatic Tires and the Like, which is fully set forth in the following specification.

This invention relates to a composition intended for stopping leaks in the air-chambers of tires for velocipedes or in india-rubber tubes or pipes subject to rupture.

My improved composition, which I term "Steganol," is intended to be introduced into the air-chambers of pneumatic tires for the purpose of stopping automatically, instantaneously, and hermetically holes or punctures accidentally made.

The composition is as follows: gutta percha, one thousand grams; copaiba or other balsam, four thousand grams; holly or other bird-lime,

four thousand grams; Swiss or Bordeaux turpentine, two thousand grams; saturated solution of celluloid, four thousand grams; chloroform or any other solvent, a quantity sufficient to dissolve the gutta-percha and other substances above mentioned.

I prefer chloroform to any other solvent.

I claim—

The herein-described composition of matter, consisting of gutta-percha, a balsam, bird-lime, turpentine, a saturated solution of celluloid, and a suitable solvent, in substantially the proportions specified.

In testimony whereof I have signed this specification in the presence of two subscribing witnesses.

ANTOINE LAVOCAT.

Witnesses:

LOUIS MAYNARD,
JEAN BAIRO.
